Primary Examiner — Selina Sikder(74) *Attorney, Agent, or Firm* — Patent Law Offices of Michael E. Woods; Michael E. Woods(57) **CLAIM**

The ornamental design for heat sink, as shown and described.

DESCRIPTION

FIG. 1 is a perspective view of a heat sink showing my new design;

FIG. 2 is a right side view thereof, the left side view being a mirror image of the right side view;

FIG. 3 is a front view thereof, the rear view being a mirror image of the front view;

FIG. 4 is a top view thereof; and

FIG. 5 is a bottom view thereof; and

FIG. 6 is a perspective view of a heat sink showing a first alternative embodiment of my new design;

FIG. 7 is a right side view thereof, the left side view being a mirror image of the right side view;

FIG. 8 is a front view thereof, the rear view being a mirror image of the front view;

FIG. 9 is a top view thereof; and,

FIG. 10 is a bottom view thereof.

The heat sink is shown broken away in FIGS. 1-10 of the drawing to indicate indeterminate length, it being understood that it has a uniform shape and appearance through its length. Portions or features of the heat sink shown in broken lines form no part of the claimed design.
